CLAIM

The ornamental design for a radiation clinical thermometer, as shown and described.

DESCRIPTION

FIG. 1 is a top, front and right side perspective view of a radiation clinical thermometer showing our new design;

FIG. 2 is a right side elevational view;

FIG. 3 is a left side elevational view;

FIG. 4 is a bottom plan view;

FIG. 5 is a front elevational view; and,

FIG. 6 is a rear elevational view thereof.

FIG. 1 has been drawn on a slightly enlarged scale with respect to FIGS. 2-6.

FIG. 1

FIG. 2
